United States Patent Office

Des. 183,443
Patented Aug. 26, 1958

183,443

DESK

Herbert E. Williams, Temple, Tex.

Application June 6, 1957, Serial No. 46,512

Term of patent 14 years

(Cl. D33—7)

FIG. 1.

Figure 1 is a perspective view of a desk embodying my new design;

Figure 2 is a rear elevational view thereof;

Figure 3 is an end elevational view thereof from the right of Figure 2; and

Figure 4 is an end elevational view thereof from the left of Figure 2.

I claim:

The ornamental design for a desk, as shown.
